UNITED STATES PATENT OFFICE.

SPENCER HEATH, OF WASHINGTON, DISTRICT OF COLUMBIA.

SCREW-PROPELLER AND METHOD OF MANUFACTURE OF THE SAME.

1,043,830.

Specification of Letters Patent. Patented Nov. 12, 1912.

Application filed December 1, 1908. Serial No. 465,552.

To all whom it may concern:

Be it known that I, SPENCER HEATH, a citizen of the United States, and resident of Washington, in the District of Columbia, 5 have invented certain new and useful Improvements in Screw - Propellers and Methods of Manufacture of the Same, of which the following is a specification.

This invention relates to screw propellers 10 and has for its object the production of a propeller having the maximum of strength and rigidity with the least possible weight of material. It is intended for general use in any of the arts in which screw propellers 15 or screw fans or blowers are employed, but on account of its extreme lightness of construction is more especially adapted for use as a propeller in the art of aerial navigation.

20 With the above object of strength and lightness and the further object of so constructing the propeller as to secure, with accuracy, any desired and predetermined form of screw, I have invented a propeller 25 and method of constructing the same which I shall describe in this specification by reference to the annexed drawings forming a part hereof, and in which:

Figures 1 and 2 are plan views of blanks 30 from which the propeller may be formed. Figs. 3, 4 and 5 are top, side, and bottom views respectively of a propeller formed from the blank of Fig. 1. Fig. 6 is an enlarged sectional view on line 6—6 of Figs. 3, 4 and 5. Fig. 7 is an enlarged sectional view on line 7—7 of Figs. 3, 4 and 5. Fig. 8 is a section corresponding to Fig. 7 when the propeller is formed from the blank of Fig. 2. Fig. 9 is a plan view illustrating 40 my method of forming the material of the propeller into the requisite shape. Fig. 10 is a modified form of Fig. 1. Fig. 11 is a perspective view of Fig. 10 folded complete. Figs. 12, 13, 14, 15, 16 and 17 are sections 45 taken on lines 13—13, 14—14, 15—15, 16—16, and 17—17 respectively of Figs. 10 and 11. Figs. 12^a, 13^a, 14^a, 15^a, 16^a, and 17^a are sections similar to Figs. 12 to 17. Fig. 18 is a longitudinal end section of a 50 folded blade. Fig. 19 is a section through the hub portion.

Similar reference characters are used throughout to designate corresponding parts.

55 The propeller is formed into shape from a

blank of sheet material, the central portion of which is formed or folded into a hollow portion or shell at and adjacent the axis of the screw, and the other parts of which form the main portions of the blades or fans, the 60 hollow central portion being extended along the back of the blades toward their extremities in such manner as to strengthen and stiffen them.

Referring to the drawings in Figs. 1 and 2, the apertures 10 at the center of the blank receive the propeller shaft. In constructing the propeller, a form or pattern 11 (Fig. 9) of fusible metal or other easily melted material is superposed upon the blank, as shown 70 in Fig. 9, and the blank is shaped or spun closely to the pattern which is afterward melted out from the hollow portions, the crevices from which the molten pattern runs being afterward spun together and the 75 seams brazed or riveted, if desired. The material is first bent or creased along the lines marked 12, the portions 13 being bent up against the faces 14 of the form to make the working surfaces or faces of the blades. 80 The portion 16 at the center of the blank is bent over the center of the form inside of the portion 17 when it is then bent over the part 16 to form the hollow shell, as shown clearly in section by Fig. 6. The portions 18 85 which are extensions from 16 and 17 are bent over upon the back of the blades in such manner that the shell formation of the center is extended along one edge of the blade, as shown in Fig. 1; or where thinner 90 material is employed or greater stiffness of blades required, the blank of Fig. 2 may be used and both edges of the blades will be reinforced, as shown clearly by Fig. 8. When the material has been formed into 95 shape, it may be brazed or soldered along the lines 19 and 20, if desired, but this has been found not always necessary, especially in the smaller sizes, since the metal has sufficient stiffness and rigidity to protect the 100 hollow portion from distortion when simply folded together without further means of security. This feature is of special value where it is desired to use aluminum or some of its compounds which are only with great 105 difficulty capable of being brazed or soldered. Should it be desirable to fasten this material, however, it may be done by means of small rivets along the edges to be secured. After the central portion has been formed 110

into the hollow shape, a hole 21 for the shaft is made in the portions 16 and 17 opposite the hole 10. The shaft may be brazed or otherwise secured directly to the metal 5 rounding these holes or a tube 22 may be secured therein and the shaft keyed or otherwise fastened in the tube.

A propeller constructed in the manner that I have described can be made in very accurate form while employing in its central or hub portion a sectional area of material which may be greater than that of any other part, and this material is so formed and disposed as to give the maximum of strength 10 and rigidity. The central shell portion may be extended toward the extremities of the blades to any extent desired by simply enlarging the portions 18, even giving the blades a double or triple thickness throughout, if desired. Where only one edge of the 15 blade is reinforced, it should be the forward edge, which is then stiffened after the manner of a quill in a wing feather, and the unreinforced portion of the blade may be left somewhat flexible, after the manner of that 20 portion of the wing feather lying back of the quill.

The modification of Fig. 1 shown in Fig. 11 possesses the same corresponding parts 30 and general characteristics as Fig. 1, the relative proportions of the parts being changed so that when the propeller is folded along the line 12 and formed to the shape of its pattern it will have the appearance 35 shown in Fig. 11. The sections in Figs. 12 to 17 show how the front portions 13 of the blades have the back reinforcing portions 18 bent over upon them and joined by thelapping seam 19 at the hub portion and its continuations in the longitudinal seam 20. In 40 Figs. 12^a to 17^a there is a slight change in the manner of lapping for the seam. Fig. 19 shows a more enlarged hub portion than Fig. 6 with the enlarged reinforcing member 45 22 for the shaft connection.

Having now fully described several of the forms in which my invention may be embodied and indicated clearly the principle thereof, what I claim is:

50 1. A propeller formed from a blank of sheet material folded longitudinally in such manner as to give multiple thickness to its parts.

2. A propeller formed from a blank of 55 sheet material and having blades with reinforcing portions bent over upon them.

3. A propeller formed from a blank of

sheet material having extensions thereon adapted to reinforce its center and blades.

4. A propeller formed from a blank of 60 sheet material and having two blades with extensions on the center and blade portions adapted to strengthen the blades and form a hollow central portion.

5. A propeller having a hollow shell-like 65 central portion, said shell-like central portion being extended toward the extremities along the edges of the blades.

6. A propeller formed from a blank of 70 sheet material and having a hollow shell-like central portion and extensions on the sides of the blades bent back to reinforce them.

7. The method of forming hollow propellers of sheet material which consists in forming the propeller of sheet material over a 75 form or pattern of easily fusible material having the requisite shape, and then melting said fusible material and causing it to run out of the hollow portions of the propeller.

8. A propeller of hollow construction 80 formed from sheet material pressed to the requisite shape and joined by a longitudinal seam extending from end to end of the propeller.

9. A propeller of hollow construction 85 formed from sheet material to the requisite shape and joined by a longitudinal seam extending from end to end of the propeller and a reinforcing member secured in the 90 center of the propeller for its shaft connection.

10. A propeller formed from a blank of 95 sheet material folded longitudinally at its central portion to form the hub, the longitudinal folds being extended to the opposing blades to reinforce them.

11. A propeller formed from a blank of sheet material folded longitudinally at its central portion to form a hub of hollow construction, the folds and hollow construction being extended throughout the length of the 100 blades.

12. A two bladed propeller formed from a single blank of sheet material extending 105 from end to end of the blades, the blank of material being longitudinally folded to form hollow blades with a hollow central portion connecting them.

SPENCER HEATH.
